UNITED STATES PATENT OFFICE

PAUL M. HENNEGAN, OF CINCINNATI, OHIO

ADVERTISING TOY

Application filed July 29, 1929. Serial No. 382,048.

The invention relates to a toy or advertising novelty.

The objects of the invention are to provide an efficient, durable and practical device by practice with, or utilization of which, persons may become familiar with operation of certain kinds of mechanism, vehicles, and the like, such as airplanes; and to provide a simple and economical construction of said device.

The invention consists in the combination of the elements, arrangement of the parts and in the details of the construction, as herein-after described and claimed.

In the drawings:

Fig. 1 is a front elevational view of the invention;

Fig. 2 is a section taken on a line corresponding to 2—2 in Fig. 1;

Fig. 3 is a front elevational view of the front piece;

Fig. 4 is a front elevational view of the rear piece with parts broken away.

In the preferred construction of the invention I provide the toy or practicing device 1 comprising the rectangular sheet material front piece 2 and the irregular formed sheet material rear piece 3. The front piece 2 has the curved slots or slits 4 and 5 in its upper and lower ends 6 and 7, respectively. Intermediate the slots 4 and 5, and positioned adjacent the side edges 8 and 9, of the front piece, are the rectangular apertures or windows 10 and 11.

Intermediate the slot 5 and the lower edge 7 are the characters 12, 13, 14, 15, 16, 17 and 18, respectively, indicating the words warm-up, take-off, climb, cruise, rightturn, descend and land which are the usual movements of an airplane attainable by predetermined operations of its engine throttle, the stick and the rudder.

The rear piece 3 is rotatably connected with the front piece 2 as by the pin 19 received through the front piece 2 and the central portion 20 of the rear piece 3.

Integrally formed with the top 21 of the rear piece 3, is the airplane reproduction 22 which may be formed from the sheet material, or imprinted upon the rear piece or both.

The reproduction 22 projects through the slot 4, of the front piece 2, and is movable adjacent the front surface 23 of the front piece, as by pivoting around the pin 19. Integral with the bottom 24 of the rear piece 55 is the indicator 25, which projects through the slot 5, in the front piece 2, and is movable adjacent the front surface 23 of the front piece 2, when the rear piece is pivoted around the pin 19. The indicator 25 is adapted to register with or point out the respective characters 12, 13, 14, 15, 16, 17 and 18.

Adjacent the side edge 26, of the rear piece 3, are the imprinted characters 27, 28, 29, 30, 31, 32 and 33, representing the words wide 65 open, open full, open slowly, throttle $\frac{3}{4}$ open, throttle down, open slowly and shut off engine, respectively, which describe the various manual operations of the throttle of a usual engine of an airplane. The characters 27, 28, 29, 30, 31, 32 and 33 are adapted to register with the window 10, when the rear piece 3 is pivoted around the pin 19, and movable with respect to the front piece 2, as by manual movement of the indicator 25 to registering 70 or pointing-out position, of its point 34, with any one of the characters 12, 13, 14, 15, 16, 17 or 18.

The characters 27, 28, 29, 30, 31, 32 and 33 are positioned on the rear piece 3, and with 80 respect to the window 10, in the front piece 2, and the location of the indicator 25 and the characters 12, 13, 14, 15, 16, 17 and 18 whereby, when the point 34 of the indicator 25 registers with any one of the characters 12, 13, 14, 15, 16, 17 or 18, the character readable through the window 10 describes the manual operation of the engine throttle of an airplane to effect the movement described by the character with which the point 34 of the 90 indicator 25 registers.

Adjacent the side edge 35 of the rear piece 3 are the imprinted characters 36, 37, 38, 39, 40, 41 and 42 representing the words stick 95 forward, stick right, stick, stick neutral, neutral, raise tail and stick back, respectively, which describe the various manual operations of the stick or rudder of a usual airplane. The characters 36, 37, 38, 39, 40, 41 and 42 are adapted to register with the window 11, 100

when the rear piece 3 is pivoted around the pin 19 as by the manual movement of the indicator 25 to registering or pointing-out position, of its point 34 with any one of the characters 12, 13, 14, 15, 16, 17 and 18.

The characters 36, 37, 38, 39, 40, 41 and 42 are positioned on the rear piece 3, and with respect to the window 11, in the front piece 2, and the location of the indicator 25, the characters 12, 13, 14, 15, 16, 17 and 18 whereby when the point 34 of the indicator 25 registers with any one of the characters 12, 13, 14, 15, 16, 17 and 18, the character readable through the window 11 describes the manual operation of the stick or rudder of an airplane to effect the movement described by the character with which the point 34 of the indicator registers.

Also, since the airplane reproduction 22 is fixed to the top of the rear piece 3 it assumes the position similar to the position of an airplane forming movements described by any one or all of the characters 12, 13, 14, 15, 16, 17 and 18 with which the point 34 of the indicator registers.

For convenience of the operator of the toy 1 the words "Engine throttle" and "Stick", and "Rudder" indicated by the numerals 43 and 44, respectively, may be imprinted upon the front of the front piece 2 adjacent the apertures 10 and 11, respectively, thereby indicating to the operator of the toy the control mechanism of an airplane to be used and its position necessary to cause the airplane to accomplish the movement described by the character to which the indicator 25 is pointed.

The holes 46 and 47, respectively, in the front piece 2 and the rear piece 3, through which the pin 19 is received, are concentric with the curved slots and the curved formation of the sets of the characters adjacent the side edges 26 and 35 of the rear piece 3, and the bottom 7 of the front piece 2.

The length of the slots 4 and 5 is dependent upon the length of the formations of the various characters on the front and rear pieces, but need not be greater than required to permit free movement of the indicator in registering position with the characters 12, 13, 14, 15, 16, 17 and 18.

For the purpose of providing means to retain the front piece 2 and the rear piece 3 in close engagement with each other, the V-shape slots 48 and 49 are formed in the rear piece 3 adjacent its top and bottom 21 and 24, respectively. The walls of the slots 48 and 49 closely engage the upper and lower walls 50 and 51, respectively, of the slots 4 and 5 in the front piece 2.

The operation of the invention is as follows:

Assume the indicator 25, as shown in Fig. 1, registers with the character 15 on the front piece. The manual movement of the indi-

cator 25 in registering position with the character 15 pivots the rear piece 3 around the pin 19 causing the characters 30 and 39, respectively, to register with a character readable through the windows 10 and 11, thereby indicating to the operator that when it is desired to "cruise" an airplane the engine throttle should be "3/4 open" and the stick should be placed in "neutral". Simultaneously, with movement of the indicator 25 in registering position with the character 15 the airplane reproduction 22 is "leveled-out" thus indicating the natural position of an airplane when it is cruising.

Assume that an operator of the toy desires to obtain information regarding the necessary manual operations of the controls of an airplane to cause the same to ascend into the air. The point 34 of the indicator 25 is manually moved in registering position with the character 19 on the front piece 2. Simultaneously with movement of the indicator the characters 27 and 42 on the rear piece 3 register with the windows 10 and 11, respectively, in the front piece and the airplane reproduction 22 assumes an upwardly and forwardly inclined position, thereby indicating to the operator of the toy that when the operator of an airplane performing a cruising movement desires to cause the airplane to ascend he manually operates the engine throttle "wide open" and puts the stick back which causes the airplane to move forward in an upwardly and forwardly inclined position represented by the reproduction 22.

In Fig. 3 is shown a modification of the front piece in which the characters 12, 13, 14, 15, 16, and 17 are represented by the abbreviations, w, t, r, c, r, and d.

It is, therefore apparent that I have invented a highly desirable toy or practicing device which may be utilized for the purpose of familiarizing persons with the manual operation of the controls of airplanes to cause the airplanes to perform predetermined movements.

Another advantage of the invention is that, since the device is made from sheet material, as paper, by means of suitable cutting dies, the same is so economically manufactured that it may be advantageously utilized and purchased by firms and persons who intend to imprint upon the front piece 2 their names and advertisements, for the purpose of giving the invention to interested persons who not only may familiarize themselves with the manual operation of the controls of an airplane, but, also, such persons are informed of the name of the giver and the products he manufactures or sells.

While I believe that the form of the invention illustrated in the drawings and referred to in the above description, as the preferred embodiment, is efficient and practicable, yet realizing that the conditions concur-

rent with the adoption of the device will necessarily vary, I desire to emphasize the fact that changes in the details may be resorted to, when required, without sacrificing any of the advantages of the invention as defined in the claims.

Various changes might be made in the general form and arrangement of parts described without departing from the invention and hence I do not limit myself to the precise details of the materials or the size and shape thereof as set forth, but consider myself at liberty to make such changes and alterations that fall within the spirit and scope of the appended and final claims.

What I claim as new and desire to secure by Letters Patent is:

1. A toy, comprising a vertical front sheet having an aperture therein and having slits therein and having characters thereon, a vertical rear sheet having its upper and lower ends protruding through said slits and being movable with respect to said front sheet and having characters thereon adapted to register with said aperture and having indicating means adapted to register with said first mentioned characters and having an airplane reproduction thereon, said characters, aperture and indicating means being so positioned that manual movement of said indicating means in registration with any one of said first mentioned characters causes a corresponding character of said rear sheet to move in registration with said aperture, thereby indicating the manual operation of the controlling mechanism of an airplane necessary to effect the movement of said second mentioned airplane as indicated by said indicator, and means whereby the normal position of said first mentioned airplane corresponds with the position of the said second mentioned airplane when said last mentioned airplane performs movements described by the respective first mentioned characters with which said indicating means registers.

2. A toy, comprising a sheet having an aperture therein and having characters thereon, a sheet movable with respect to said first mentioned sheet and having characters thereon adapted to register with said aperture and having indicating means adapted to register with said first mentioned characters and having an airplane reproduction thereon, said aperture and indicating means being so positioned that manual movement of said indicating means in registration with any one of said first mentioned characters causes a corresponding character of said second mentioned sheet to move in registration with said aperture, thereby indicating the manual operation of the controlling mechanism of an airplane necessary to effect the movement of said second mentioned airplane as indicated by said indicator, and means whereby the normal position of said first

mentioned airplane corresponds with the position of the said second mentioned airplane when said last mentioned airplane performs movements described by the respective first mentioned characters with which said indicating means registers.

3. A toy comprising a pair of sheets, one of said sheets having an airplane imprinted thereon, an indicator on one of said sheets, and means whereby movement of said indicator indicates the position of the controls of an airplane to effect a predetermined movement of said second mentioned airplane, and means whereby said first mentioned airplane assumes the position corresponding to the position of said second mentioned airplane when said controls are operated as indicated by said indicator.

4. A toy comprising a pair of sheets rotatably connected with each other, one of said sheets having a machine pictured thereon, and having a plurality of sets of characters describing the operation of manual controls of the machine and having an indicator thereon, the other of said sheets having a plurality of apertures therein and having characters thereon describing the movements of said machine, whereby manual movement of said indicator in registering position with one of said movement describing characters causes the one set of said control describing characters to register with said apertures thereby indicating to the operator the position of said controls necessary to effect the movement of said machine described by the movement character with which said indicator is registered, said pictured machine adapted to be positioned corresponding to the machine position when the controls are operated as indicated by said set of characters registering with said apertures.
